CRATING SYSTEM FOR SHEET MATERIAL
OR THE LIKE

James W. McCracken, Leechburg, Pa.

Application March 4, 1952, Serial No. 274,726

10 Claims. (Cl. 206—60)

1

This invention relates to a new crating system for heavy material such as steel sheets or the like. More particularly, it is an improvement upon my application Serial No. 226,443, filed May 15, 1951, and pertains to a new kind of crate made of a material like wood and to a new system of crating for handling or shipping flat sheet material such as steel sheets having a high grade finish.

For some time it has been customary practice for manufacturers of high grade steel sheets such as those made by cold rolling processes and provided with expensive and valuable finishes, to be shipped in wooden crates. Such sheets are supplied in a variety of thicknesses and of sizes such as, for example, as six feet by twelve feet, four feet by ten feet, three feet by ten feet, three feet by eight feet, two and one-half feet by eight feet and many others. Because of weight restrictions, for example, imposed by consignees or others the number of sheets so shipped, and consequently the weight, in a single crate was not large. In some cases the total weight of steel sheets and crate could not exceed about 800 pounds. It is evident therefore that the greater the weight of the wooden crate, the less, generally speaking, the weight of metal sheets that could be shipped in that crate. Moreover, prior crates were very expensive, difficult to handle, involved considerable fabrication, were of unattractive appearance and had relatively little salvage value.

In the crating system of this invention, a new crate and method of crating is provided having many advantages. For example, in the new crate standard materials can be used with a minimum of assembly labor required therein. Such labor involves no more than rip or crosscut sawing operations and the nailing together of the structural parts of the assembly. In the new crate there is much less of a handling problem because of the material reduction in the weight thereof and in the amount of labor required to construct it. Although the new crate may be made right-side-up from the beginning, in general the side and end rails thereof will be united to form a rectangular starting frame to which the ledge rail sections, the bottom crosspieces and any bottom rails will be applied before that portion of the incomplete assembly is turned over. In the new construction, subassemblies, for example, of the side rail and ledge rail sections may be prepared beforehand for the rapid completion of a new crate in whatever size is required. The bottom rails, where used, are available,

2

to act as skids but also interlock the respective ledge rails and bottom crosspieces to the balance of the complete structure. By providing in the new system for the use of high grade structural side rails made of a single piece of material like green Douglas fir, the new crate remains relatively inflexible and yet retains enough "give" to withstand impact shocks which might otherwise crack or shatter part of it. The remainder of the new crate may be constructed of kiln-dried or air-dried or green lumber depending upon the purchase prices at the time being. In the new crate further, the relatively small section of the side rails makes a larger supply of suitable lumber readily available therefor. In the new construction, also, ledge rails of longitudinally spaced sections are provided on which side edges of the sheet material rest to afford preventive measures against sagging or deflection of the sheet material along the length thereof when in the new crate. The metal binding strips that are used in the older practice are not required in this new construction. The salvage value of the new crate is high relative to other forms of crates employed. The new crate is susceptible of being given an extremely attractive appearance at low cost while at the same time protecting both the finish and the flatness of the sheet material carried thereby.

Other objects and advantages will be apparent from the following description and from the drawings, which are illustrative only, in which:

Figure 1 is a plan view of the lower portion of a new crate made in accordance with this invention;

Figure 2 is a view in side elevation of the crate shown in Figure 1 with top crosspieces in their relative final assembly positions and with the right-hand end of the crate as viewed in Figure 2 in section taken along line II—II of Figure 1;

Figure 3 is a view in partial section taken along line III—III of Figure 1 after the crate in Figure 1 has been filled and the entire assembly thereof completed;

Figure 4 is a perspective view of a corner of the crate shown in the preceding figures with the side rail broken and the liners and sheet material removed; and

Figure 5 is a detailed view partially in section of a variant means for holding the sheet material tightly in place in the new crate.

Referring to the drawings, in the new crate, a pair of side rails 10 will, in general, determine the height of the sheet material packing space in the crate when finally assembled as shown in

Figure 3. Lumber suitable for side rails comes in standard lengths such as ten feet which closely matches one of the standard lengths of sheets such as cold rolled steel sheets of high quality which are generally shipped in crates. Usually, standard lumber sections such as two-by-fours will be utilized. Where not of desired section, a simple sawing operation on a power saw will prepare the wood for use. The lumber generally used will be dressed or at least semi-dressed lumber, although such is not necessary. With fully dressed lumber it is of course necessary to make due allowance for the smaller dimensions thereof. For example, a two-by-four after being fully dressed has a section one and five-eighths inches by three and five-eighths inches in normal lumber mill practice.

Side rails 10 are parallel and generally extend the entire length of the new crate. Each side rail 10 is preferably made of a single piece of high-grade lumber such as select structural green Douglas fir. Thereby, when the new crate is supported intermediate the ends there will be sufficient rigidity when the side rails are assembled with the remainder of the new structure to prevent any material deflection. At the same time, the relative inflexibility of the side rails 10 is not so great that, with the remainder of the structure, they fail to provide enough yield, which generally can't be observed, to resist damage under impact shock such as might occur if the new crates are dropped as sometimes happens in the course of shipment.

Ledge rails 11 may also readily be constructed of standard sizes of lumber. Because of their relatively short lengths, they can be made from pieces of wood which otherwise might have to be scrapped. Each ledge rail 11 is composite in that it comprises longitudinally spaced sections 11a affixed to the under side of the respective side rails 10 by nails 12. Other fastening means such as wood screws, with for example, countersunk heads may be used but such a construction normally would add to the cost of the crate and is not essential. The height of the side rails 10, that is, the distance between the top of the ledge rails 11 and the respective tops of the side rails 10 determines the space in the new crate available for liners, any tightening strips and the steel sheets to be shipped in the crate. Each side rail 10 and its accompanying ledge rail sections 11a may comprise a subassembly of any desired length. In that way, whatever length crate is required is obtainable by only cutting the subassembly, if required, to the desired length of the sheet material that will be shipped.

A plurality of spaced bottom crosspieces 14 are employed as shown in Figures 1, 2 and 4 along the length of the new crate finally being assembled. These bottom crosspieces 14 are affixed in place as by nails 15. Thus the upper surface of the bottom crosspieces 14 and the tops of the ledge rail sections 11a define a plane for the inside bottom of the wooden portion of the new crate and also define a supporting surface across and around the entire edge of heavy sheets being shipped therein. Hence, there is no sagging and the sheets remain flat.

The bottom crosspieces 14 extend between the outer sides of the respective side rails 10 to the under sides of which they are nailed. The respective ends of the respective bottom crosspieces intermediate the ends of the crate fit into the spaces between the ends of adjacent ledge rail sections 11a. The thickness of the ledge rails 11 and of the bottom crosspieces 14 are prefer-

ably the same. Thus, the support furnished to the sheet material that is placed in the new crate which occurs around the edges is due to the action of the top surface of the respective ledge rail sections 11a which extend inwardly of the inner sides of the side rails 10 and to the portion of the tops of the respective bottom crosspieces 14 which form a continuation of the clear top surface portion of the respective sections 11a. The space defined by the inner sides of the side rails 10 within the new crate will be taken up by the size of the sheet material placed in that new crate. In general, the sheet material so shipped has a clearance of one-eighth to one-fourth of an inch on each side between its edge and the side rails 10. Such a clearance enables the sheet material to be readily placed in and removed from the new crate and at the same time insures the aforesaid support around the entire edge of the sheet material.

The bottom crosspieces 14 at the ends of the new crate, in the embodiment shown, extend beyond the ends of side rails 10 a distance equal to the width of end crosspieces 17 which are also made of single lengths of lumber. Further, in the embodiment shown, bottom rails 16 are provided generally made out of a single piece of lumber. The tops of the bottom rails 16 bear against the bottoms of the ends of the bottom crosspieces 14 and the bottoms of the ledge rail sections 11a to which and to side rails 10 they are fastened by suitable nails. In general, in constructing these new crates, cement coated box nails are preferably used to obtain the increased holding power thereof whenever the new crate is to be employed in connection with heavy duty service such as the packaging of steel sheets. In addition to serving as skids whenever that mode of movement is employed, the bottom rails 16 also interlock the ends of the bottom crosspieces 14 and the ledge rail sections 11a to the remainder of the structure of the new crate.

The end crosspieces 17 may be made from the same size of material as the side rails 10 and can be prepared from the lumber as a general rule simply by sawing it to length. Since steel strip sheets also generally come in standard sizes, it is again possible to have a stock pile of precut lengths of end rails 17 and bottom crosspieces 14 stockpiled and ready for final assembly into a new crate as it is needed. Preferably, the height of the end rails 17 will be the same as that of the side rail 10 as shown in Figures 2 and 4. The end rails 17 are affixed as by nailing them to the ends of the side rails 10 by nails 18 shown in dotted outline in Figure 4. The top surfaces of the end rails 17 are on a level with the tops respectively of the side rails 10. Short corner strips of scrap metal may be made and nailed around the corners of the crate after the end crosspieces 17 are affixed to afford somewhat additional protection at a prominent part to protect the crate somewhat more if it is dropped on its corner in the course of being handled in a freight or express shipment. Normally such corner strips are not required.

As assembled to the point just described, the new crate is ready for a bottom liner 20. These liners may be made of a good quality paperboard such as "Upson" board or wood fiberboard. One or both of the outer surfaces thereof may be decoratively finished and waterproofed to increase the moisture resistance of the crate. Such legends, coloring and/or further decorative effect as desired may also be placed thereon. Such liner boards as board 20 come in standard sizes

as a general rule and are readily cut with a saw to the precise dimension required. In the instant case, the dimensions of the board must conform to the area inside the side rails 10 and the end rails 17 overlying ledge rails 11 and closing the interstices or gaps between the bottom crosspieces 14. Liners such as bottom liners 20 are substantially unimpaired in quality or appearance when the crate is unpacked and may therefore be used for other purposes or re-used for the same purpose.

Sheet material to be shipped such as cold-rolled steel sheets 21 are placed on the bottom liners 20 between the side rails 10 and the end rails 17 as shown in part in Figure 3. These sheets 21 are only schematically shown in Figure 3 inasmuch as they may vary materially in thickness. For some surface finishes, for example, oiled sheets of paper 22 may be placed between the respective sheets of metal 21 and such a sheet may be placed between liner 20 and the underside of the lowermost sheet 21 to protect the sheets against any weather or moisture intrusion that might affect the surface finish. The sheet material 21 will generally have a clearance of about one-eighth inch around its entire edge between such edge and the inside of the new crate. At the same time the side edges of sheets 21 will be fully supported by ledge rails 11 to keep the sheets from sagging between crosspieces 14.

After the requisite number of steel sheets 21, for example, have been placed in the new crate on bottom liner 20, a further oiled sheet 23 of paper or other protective material may be placed on top of the sheets 21 and a top liner 24 placed thereon in turn. Top liner 24 may be similar in all respects to bottom liner 20 except that if a but a single side of top liner 24 is waterproofed or colored, that side will generally be uppermost 40 rather than lowermost as in the case of liner 20. If the liners 20, 24, metal sheets 21 and separators 22, 23 are substantially flush with the tops of rails 10, it will enable top crosspieces 25 to be placed directly across the upper surface of liner 24, which will be generally at the level of the bottoms of the top crosspieces 25. In some cases there may be or it may be desirable to leave a little clearance between the top of liner 24 and the plane defined by the tops of side rails 10 and end rails 17. In that case, tightening strips 26 may be laid along the sides of the new crate on top of liner 24 against the side rails 10, as shown in Figure 3. These tightening strips 26 may be cut from paperboard or fiberboard scrap left over in preparing liners 20 and 24, for example. When top crosspieces 25 are nailed in place as by nails 27 with tightening strips 26 in place the entire crate and its contents form a relatively inflexible unitary package ready for shipment.

A variant is shown in Figure 5 in that the sheet material such as sheet materials 21, and liners like liners 20 and 24 may be held firmly in place in the space defined by and between the inner sides of side rails 10 and end rails 17 by the use of tightening strips 28. Tightening strips 28 may be made of two or more pressed down on the top of liner 24 and against the adjacent side of a top crosspiece 25. In that position nails 29 may be used to fasten strips 28 to the new crate. Generally, at least two such tightening strips 28 will be employed in spaced similar distance relation to each other and to the ends of the new crate. Such variant is another means

by which the contents of the new crate are held against relative movements in the new crate in the course of shipment.

The top crosspieces 25 have a length which is the same as that of the bottom crosspieces 14 and just spans the entire width of the new crate, including the thickness of the side rails 10 on each side thereof. Indeed the dimensions of top and bottom crosspieces can be identical. The top pieces 25 at the ends, preferably will overlie the top surfaces of the respective end rails 17 to help strengthen the ends of the crate and avoid any projecting edge to catch during the handling of the shipment. Along the length of the new crate the top crosspieces 25 are spaced at selected intervals as in the case of and generally directly above the bottom crosspieces 14.

The assembly so completed with the materials to be shipped therein presents an economical and satisfactory crate which has a highly pleasing appearance and high salvage value. At the same time it keeps the metal sheets flat and protected and increases the weight of metal or other sheet material that can be shipped in the new crate for a given dimension and weight of shipment and it solves a problem which has long existed in this particular art.

The invention is not to be limited except as may be done by the scope of the appended claims.

I claim:

1. A substantially rectangular crate for sheet material or the like, comprising in combination, parallel side rails extending along the length of said crate, said side rails being rectangular in section, ledge rails affixed to said side rails and extending inwardly thereof respectively adjacent the bottoms thereof, said ledge rails having longitudinally spaced sections, bottom crosspieces extending between the outer sides of said side rails and being positioned in the spaces between said sections, said bottom crosspieces being affixed to the adjacent bottoms of said side rails respectively, the tops of said sections and said bottom crosspieces being generally in the same plane, end rails affixed to said side rails, and top crosspieces connecting said side rails adjacent the tops thereof.

2. A substantially rectangular crate for sheet material or the like, comprising in combination, parallel side rails extending along the length of said crate, said side rails being rectangular in section, ledge rails affixed to said side rails and extending inwardly thereof respectively adjacent the bottoms thereof, said ledge rails having longitudinally spaced sections, bottom crosspieces extending between the outer sides of said side rails and fitting in the spaces between said ledge rail sections, said bottom crosspieces being affixed to the bottoms of said side rails respectively, the tops of said bottom crosspieces and said ledge rail sections being generally in the same plane, end rails affixed to said side rails, top crosspieces connecting said side rails adjacent the tops thereof, and bottom rails extending longitudinally beneath said ledge rail sections and the respective ends of said bottom crosspieces, said bottom rails being affixed thereto to interlock said ledge rail sections and bottom crosspieces to said crate.

3. A substantially rectangular crate for sheet material or the like, comprising in combination, relatively flexible parallel side rails extending along the length of said crate, said side rails being of a material such as select structural

green Douglas fir, said side rails being rectangular in section, ledge rails affixed to the under side of said side rails and inwardly of the inner sides thereof, said ledge rails having longitudinally spaced sections, bottom crosspieces affixed to the under sides of said side rails respectively to connect them, said bottom crosspieces being positioned in the spaces between said sections, the tops of said sections and said bottom crosspieces being generally in the same plane, end rails affixed to the ends of said side rails, and top crosspieces connecting said side rails adjacent the tops thereof, said top crosspieces being generally positioned above said bottom crosspieces.

4. A substantially rectangular crate for sheet material or the like, comprising in combination, relatively flexible parallel side rails extending along the length of said crate, said side rails being of a material such as select structural green Douglas fir, said side rails being rectangular in section, ledge rails affixed to the under side of said side rails and inwardly of the inner sides thereof, said ledge rails having longitudinally spaced sections, bottom crosspieces affixed to the under sides of said side rails respectively to connect them, said bottom crosspieces being positioned in the spaces between said sections, the tops of said sections and said bottom crosspieces being generally in the same plane, end rails affixed to the ends of said side rails, top crosspieces extending between the outer sides of said side rails and affixed to the tops thereof respectively, and means for holding sheet material tight against relative movement in the space defined by the inner sides of said side rails and end rails.

5. A substantially rectangular crate for sheet material or the like, comprising in combination, relatively flexible parallel side rails extending along the length of said crate, said side rails being of a material such as select structural green Douglas fir, said side rails being rectangular in section, ledge rails affixed to the under side of said side rails and inwardly of the inner sides thereof, said ledge rails having longitudinally spaced sections, bottom crosspieces affixed to the under sides of said side rails respectively to connect them at and intermediate the ends of said crate, said bottom crosspieces being positioned in the spaces between said sections, the tops and bottoms of said sections and said bottom crosspieces being generally in the same plane, end rails affixed to the ends of said side rails, bottom rails extending along the length of said crate and fastened to the bottoms of said sections and said bottom crosspieces generally in a position below said side rails, and top crosspieces connecting said side rails adjacent the tops thereof, said top crosspieces being generally positioned above said bottom crosspieces.

6. A substantially rectangular crate for sheet material or the like, comprising in combination, relatively flexible parallel side rails extending along the length of said crate, said side rails being generally rectangular in section, ledge rails of generally rectangular section affixed to the under sides of said side rails respectively and extending along the length of said crate, said ledge rails comprising longitudinally spaced sections extending inwardly of the inner sides of said side rails, bottom crosspieces extending between the outer sides of said side rails and connected to the under sides of said side rails, said bottom crosspieces being positioned in the spaces

5 between the respective ends of said sections of said ledge rails, the tops of said ledge rails and bottom crosspieces being generally in the same plane, end crosspieces connected to the respective ends of said side rails and closing the ends of said crates, the tops of said end crosspieces being generally in the plane of the top of said side rails, the bottoms of said end crosspieces being generally in the same plane as the bottoms of said side rails, and top crosspieces extending between the outer sides of and affixed to the tops of said side rails.

7. A substantially rectangular crate for sheet material or the like, comprising in combination, relatively flexible parallel side rails extending along the length of said crate, said side rails being generally rectangular in section, ledge rails of generally rectangular sections affixed to the under sides of said side rails respectively and extending along the length of said crate, said ledge rails comprising longitudinally spaced sections extending inwardly of the inner sides of said side rails, bottom crosspieces extending between the outer sides of said side rails and connected to the under sides of said side rails, said bottom crosspieces being positioned in the spaces between the respective ends of said sections of said ledge rails, the tops of said ledge rails and bottom crosspieces being generally in the same plane, end crosspieces connected to the respective ends of said side rails and closing the ends of said crates, the tops of said end crosspieces being generally in the plane of the top of said side rails, the bottoms of said end crosspieces being generally in the same plane as the bottoms of said side rails, top crosspieces extending between and affixed to the tops of said side rails, bottom rails extending longitudinally beneath said ledge rail sections and the respective ends of said bottom crosspieces, said bottom rails being affixed thereto to interlock said ledge rail sections and bottom crosspieces to said crate.

8. A substantially rectangular crate for sheet material or the like, comprising in combination, relatively flexible parallel side rails extending along the length of said crate, said side rails being generally rectangular in section, ledge rails of generally rectangular section affixed to the under sides of said side rails respectively and extending along the length of said crate, said ledge rails comprising longitudinally spaced sections extending inwardly of the inner sides of said side rails, bottom crosspieces extending between the outer sides of said side rails and connected to the under sides of said side rails, said bottom crosspieces being positioned in the spaces between the respective ends of said sections of said ledge rails, the tops of said ledge rails and bottom crosspieces being generally in the same plane, end crosspieces connected to the respective ends of said side rails and closing the ends of said crates, the tops of said end crosspieces being generally in the plane of the top of said side rails, the bottoms of said end crosspieces being generally in the same plane as the bottoms of said side rails, board liners fitting within the space defined by the inner sides of said side rails and end crosspieces, and top crosspieces extending between the outer sides of and affixed to the tops of said side rails.

9. A substantially rectangular crate for sheet material or the like, comprising in combination, relatively flexible parallel side rails extending along the length of said crate, said side rails being generally rectangular in section, ledge rails of generally rectangular section affixed to the under

sides of said side rails respectively and extending along the length of said crate, said ledge rails comprising longitudinally spaced sections extending inwardly of the inner sides of said side rails, bottom crosspieces extending between the outer sides of said side rails and connected to the under sides of said side rails, said bottom crosspieces being positioned in the spaces between the respective ends of said sections of said ledge rails, the tops of said ledge rails and bottom crosspieces being generally in the same plane, end crosspieces connected to the respective ends of said side rails and closing the ends of said crates, the tops of said end crosspieces being generally in the plane of the top of said side rails, the bottoms of said end crosspieces being generally in the same plane as the bottoms of said side rails, tightening strips extending along the respective inner sides of said side rails, and top cross pieces extending between and affixed to the tops of said side rails.

10. A substantially rectangular crate for sheet material or the like, comprising in combination, relatively flexible parallel side rails extending along the length of said crate, said side rails being generally rectangular in section, ledge rails of generally rectangular section affixed to the under sides of said side rails respectively and extending along the lengths of said crate, said ledge rails comprising longitudinally spaced sections
